UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed March 13, 1924, Serial No. 699,119. Renewed June 29, 1927.

My invention relates to mining machines.

An object of my invention is to provide an improved mining machine. Another object of my invention is to provide an improved mining machine of the so-called universal type. A further object of my invention is to provide an improved mining machine having improved and simplified adjusting means for the cutting mechanism permitting a very wide range of cutting in a relatively narrow machine. A still further object of my invention is to provide an improved mining machine having improved supporting and adjusting mechanism for the cutting mechanism thereby whereby the machine may cut upon a trackway with the cutting mechanism upon the bottom and outside the trackway. Other objects and advantages of my invention will hereinafter more fully appear.

20 In the accompanying drawings I have shown for purposes of illustration one form which my invention may assume in practice.

In these drawings,—

Fig. 1 is a side elevation of a mining machine in which the illustrative embodiment of my invention is incorporated, with the cutter bar broken away.

Fig. 2 is a plan view of such a mechanism with the cutter bar broken away.

Fig. 3 is a view partially in plan and partially in section showing portions of the adjusting mechanism for the cutter bar and its supporting mechanism.

Fig. 4 is a view on the section line 4—4 of Fig. 3, being a vertical sectional view through portions of the cutting mechanism actuating, supporting and adjusting mechanism.

Fig. 5 is a horizontal section showing portions of the truck driving mechanism, the bar adjusting mechanism, transmission mechanism, etc.

Fig. 6 is a section approximately on a plane corresponding to the section line 6—6 of Fig. 5.

Fig. 7 is a detail sectional view taken on a plane corresponding to a line 7—7 of Fig. 5.

Fig. 8 is a detail sectional view illustrating a portion of the truck wheel driving mechanism.

My invention constitutes an improvement over the invention of one Morris P. Holmes described and claimed in his application Ser. No. 694,139, filed Feb. 20, 1924, and such parts of the mechanism as are not specifically my

invention will be described in no more detail than is essential for the purpose of disclosing the mode of operation of the improved construction.

A truck 1 is provided which is movable along a trackway 2, the truck being supported on wheels 3 which are connected for rotation together by a chain 4. The wheels are capable of being driven either at a fast or at a slow speed, these speeds corresponding respectively to the proper speeds for propulsion about a mine and for a cutting speed, and the wheels may also be held stationary if desired. Mechanism for accomplishing these results is, however, not per se my invention and accordingly has not been disclosed in minute detail. The truck wheels may be driven by the chain 6 through friction controlled motor driven driving mechanism 7 from a motor 8 at a suitable speed for running around the mine, it being possible by reversing the motor to run in either direction, and also possible to interrupt the driving connection so that the wheels may rotate freely, and further that a driving sprocket 10, also driven from the motor 8 through suitable reduction and reversing gearing, not shown, is capable of driving the truck wheels through a flexible connection 11 at a slow or cutting speed in either direction without reversing the motor, and this mechanism is of such nature that the truck wheels may be locked with the aid of the member 10 and may also be wholly freed from any influence of the driving mechanism of the member 10. In other words, either the connection 6 or the connection 11 may constitute a driving connection, while the other is freely rotatable. The motor 8 also serves to drive a pair of shafts 15, 16, the shaft 15 being driven at an equiangular rate with the armature shaft of the motor and being in fact in alignment with the latter while the shaft 16 is capable of being rotated in opposite directions or held stationary by suitable power transmission connections between the motor and said shaft, as hereinafter more fully described and which are disclosed in the aforementioned application of the said Holmes.

The cutting mechanism herein comprises an elongated cutter bar 20 provided with a cutter chain 21 of well known form and having cutter bits 22 which are propelled by a cutter chain driving sprocket 23 which is adapted to be driven by a shaft member

24, suitable clutch mechanism 25 being provided for connecting the cutter chain driving sprocket to the shaft 24 or releasing it therefrom, which mechanism is operable through suitable connections 26 from the exterior of the machine as at 27. The cutter bar 20 is rotated with a plate member 28 which carries at its periphery an internal gear 29. The plate member 28 and gear 29 are held for rotation upon an axis coincident with the axis of the shaft 24 by suitable flanges 30 secured to the housing 31 which encloses the cutter chain driving sprocket driving mechanism described, and also bar swinging mechanisms. For the purpose of swinging the bar relative to this housing, there is provided mechanism shown only in part herein, but of the same type with other mechanism which will later be described and accordingly for the present, it will suffice to say that this mechanism includes a pinion 32 rotatable upon a vertical axis fixed relative to the housing 31 and driven by a worm wheel 33 which is in turn driven by a worm 34 upon a shaft 35, through friction controlled means for effecting rotation of the worm in opposite directions and at unequal speeds. The construction of this mechanism as stated will be made clearer in connection with the description of other parts of similar construction hereafter, it being understood that it comprises elements corresponding to those of this other mechanism. This mechanism per se is not, however, my invention but is also disclosed in the application of the said Morris P. Holmes.

The housing 31 is provided with suitable guides 36 bolted or otherwise held thereto which slide in guideways 37 secured to a member 38 which will hereafter be more fully described. The member 24 is herein adapted to be raised or lowered and to raise or lower with it the cutter bar and its supporting means by mechanism generally similar to that disclosed in the application of said Morris P. Holmes and in the application of one Cornelius G. Boudette, Ser. No. 694,222, filed Feb. 21, 1924. It will be observed that the member 38 herein carries a casing 40 within which there is enclosed a large bevel gear 41 which is connected in non-rotative relation to a nut element 42 by machine screws 43. Coaxial with the nut element 42 is a splined sleeve 44 which at its upper end is splined to a sleeve member 45 having projecting ribs or splines 46, 46' thereon, the splines 46 engaging the alternate discs of a friction clutch 47, the other discs of which clutch are held by splines 48 against rotation relative to the housing 40. The splines 46' constitute clutch elements and are connectible by a sliding clutch sleeve 50 with corresponding splines 51 upon the exterior of the member 42. Slidable through openings 52 in a rib on the frame 40 are plungers 53 which

are adapted to be engaged on upward movement of the sleeve 50 to force the clutch discs into engagement and lock the member 45 and so the member 44 against rotation, while on downward movement of the sleeve 46 the clutch is released and the part 44 may rotate relative to the casing 40. Suitable clutch operating mechanism 55 is provided for raising and lowering the clutch sleeve 46. It will be evident, when it is noted that the member 24 is formed at its upper end in the form of a screw 56 having splineways 57 therein cooperating with splines 58 upon the member 44 and having its thread engaged with the nut 42 and that it has, moreover, a collar 58 thereon engaging a suitable combined bearing and supporting means 59 for the housing 31 and the mechanism supported thereby, that the member 24 is adapted to effect elevation and lowering, or perhaps in view of the various adjustments possible it would be better to say, approach and separation between the housings 31 and 40. It will be evident from an inspection of Fig. 4 that with the parts in the position shown, the bar is capable of cutting on the bottom, while when it is desired to propel the machine around the mine, the mechanism may be operated to raise the bar a substantial distance above the bottom and accordingly any difficulty with the bar striking the bottom or the track during passage through hollows in the trackway or in starting up hill will be eliminated. To recapitulate, it may be stated that when the clutch sleeve 50 is in raised position forcing the plungers 53 upward, rotation of the nut will cause raising or lowering of the housing 31 and of the bar depending upon the direction of rotation of the member 41, while with the sleeve in its lower position, connecting the splines 46' and 51, there will be no relative movement between the housings 31 and 40 and the cutter chain may be driven to effect cutting.

The member 38 which was referred to previously is in the form of a supporting casing member which encloses certain gearing and which is of such dimension that it can support the guideways 37 in such relation to the trackway that the cutting mechanism may be placed upon the bottom outside the trackway. It will of course be understood that it may be made of greater length than that shown. This member 38 at its upper end is provided with a large internal gear 61 which serves in cooperation with an annular member 62 to support the member 38 and the parts connected thereto in rotative relation to a forwardly projecting housing 63 which is rotatable on a horizontal longitudinally extending axis through mechanism which will be later described. It will be observed that the member 63 has secured thereto an internal gear 64 which is held for rotation on the front end of the frame of the mining machine

by a suitable flanged sleeve member 65 bolted by bolts 66 to said front end. It will be noted that a pinion 67 is arranged upon the shaft 16 and cooperates with the gear 64 to effect 5 rotation of the latter and with it of the housing 63. Suitable locking means of any suitable construction capable of locking the gear 64 against rotation may be provided, and such a mechanism of the type similar to that 10 employed by the said Morris P. Holmes in his application previously referred to, is designated at 68.

From what has been said previously, it will be obvious that the head 63 and all the parts 15 supported thereby may be rotated in either direction or held stationary. The shaft 15 projects through the gear 64 inwardly into the casing 63 where it carries a bevel pinion 70 which drives a bevel gear 71 secured to a 20 shaft 72 coaxial with the gear 61 and having its axis perpendicular to the axis of the shaft 15 extended. The shaft 72 is suitably journaled in bearings 73, 74 and at its lower end carries a bevel driving pinion 75 driving a 25 bevel gear 76 rotatable on an axis perpendicular to the axis of the shaft 72 and disposable either parallel to the shaft 15 or at various angles to a line parallel to the shaft 15 but intersected by the axis of the shaft 30 35 upon which the gear 78 is secured. This last mentioned shaft, designated 78, is suitably journaled as at 79 in the member 38 and carries a pinion 80 meshing with and adapted to drive the gear 41.

50 It will be observed that the shaft 72 above the gear 71 thereon carries a pinion 81 which meshes with and is adapted to drive pinions 82, 83 which are arranged on shafts 84, 85 whose axes lie herein in a plane to which the 55 axis of the shaft 15 is perpendicular. These shafts carry worms 86, 87 respectively, of which the worm 86 is of the smaller lead and these worms also differ in that the thread upon one is a left hand thread while upon 60 the other it is a right hand thread. Suitably journaled as at 88 there is provided a transversely extending shaft 89 which carries loosely thereon a pair of worm wheels 90, 91 of which the worm wheel 90 cooperates with 65 the worm 84 while the worm wheel 91 cooperates with the worm 85. Suitable friction clutch mechanism is provided for connecting either of these worm wheels to the shaft 89, the clutch mechanism cooperating with the 70 worm wheel 90 being designated 92, while the other is designated 93, and means controllable from either end of the shaft 89 and including hand wheels 94, 95 is arranged for effecting loading of the clutches 92 and 93. 75 Between the worm wheels 90 and 91 there is a worm 97 which engages a worm wheel 98 fixed upon a shaft 99 and carrying a pinion 100 which engages with the internal gear 61. It will be apparent that since the shaft 99 is 80 journaled in fixed relation to the member 63,

rotation of the pinion 100 will effect rotation of the internal gear 61 and so will cause the member 38 to pivot about the axis of the shaft 72 and will effect swinging of the casings 40 and 31 and of the cutter bar across 70 the front end of the machine. The mechanism including the shaft 35, worm 34, and worm wheel 33, etc. employed for the purpose of swinging the cutter bar is identical in principle and in general mode of operation 75 with that last described for effecting pivotal movement of the member 38, but the proportions are preferably so varied as to cause bar swing at an equal angular rate to that of swing of the parts supported by frame 88 80 when both are running at once, the fast feeds being in opposite directions, and so also the slow swings. Of course either swing is possible separately. It will be understood that both the bar swinging mechanism and the mechanism for swinging the member 38 are self-locking, because the worm 34 and the worm 97 must be turned positively in order to permit rotation of the worm wheels 33 85 and 98.

90 The driving connections between the motor 8 and the shafts 15 and 16 and the chain sprocket 10 will now be briefly described. The forward end of the motor armature shaft has connected thereto (as shown in Fig. 6) a sleeve 101 which is provided with a driving pinion 102. This pinion meshes with and drives a larger spur gear 103 which is carried upon a horizontal longitudinally extending shaft 104 suitably journaled within 95 the machine frame. At its forward end the shaft 104 carries a bevel pinion 105 which meshes with and drives a pair of coaxial oppositely facing bevel gears 106 and 107. The latter are connectable by friction clutch 100 mechanisms which are generally designated 108 and 109 alternatively with a transverse horizontal shaft 110. These clutch mechanisms are operated by suitable shipper mechanism including a shipper yoke 111 and an 105 operating handle 112 carried at the top of the frame. The shaft 110 is provided with a worm 113 (see Fig. 7) which meshes with a worm wheel 114 secured to a horizontal longitudinally extending shaft 115 alined with the 110 shaft 16 and suitably journaled within the machine frame. This shaft 115 carries a worm 116 which meshes with and drives a worm wheel 117. As shown the worm wheel 117 is connectible by a clutch mechanism 118 to a shaft 119 (see Fig. 5) which carries the chain sprocket 10. As shown in Fig. 7 the shaft 16 is connectible to the drive shaft 115 by suitable clutch mechanism 120. Referring more specifically to the truck driving mechanism it will be observed that the rear end of the motor armature shaft has secured thereto a spur pinion 121 which meshes with a spur gear 122 fixed to a horizontal longitudinally extending shaft 123. This shaft 123 has se- 115 120 125 130

cured thereto a worm 124 meshing with a worm wheel 125 which drives, through the friction controlled mechanism 7 mentioned above, the truck wheels. It will be observed that the shaft 15 is arranged in alinement with the motor armature shaft and is keyed at its rear end within a coupling member 126 which is non-rotatably secured to the sleeve 101 carrying the driving pinion 102, the parts constituting a flexible coupling. It will also be seen that the shaft 16 may be rotated in one direction or the other under the control of the clutch mechanisms 108, 109 or may be entirely disconnected from the motor by means of the clutch mechanism 120. It will also be noted that the driving sprocket 10 may be connected to or disconnected from the motor at will by means of the clutch mechanism 118. The shaft 15 is driven at all times by the motor armature shaft. As these driving connections are clearly described in the above mentioned application Ser. No. 694,139 further description of the same is herein submitted to be unnecessary.

From the description which has been given, the mode of operation of this mechanism will be readily apparent. The mechanism may be propelled about the mine, the truck wheels being driven by the flexible connection 6 through the mechanism 7 and when the desired place for a cut to be made is reached, it will be evident that the cutter bar supporting mechanism can be adjusted to insert a kerf in a wide variety of planes. It is true that a shearing cut cannot be inserted in the middle of an entry, but shearing cuts may be made in various vertical planes in a face in advance of the machine and at either side of the center line of the track 2. One of the most important features that may be accomplished by this mechanism is the making of a cut on the bottom, and with the machine propelled during sumping and withdrawing cuts along the trackway. I will therefore describe the operations requisite for the accomplishment of this result in detail and leave further operations without full description in view of the fact that from what will be said, one skilled in the art will readily understand what operations are necessary to accomplish the insertion of any desired cuts within the range of the machine.

Assume, therefore, that the machine is standing upon the trackway 2 with the cutter bar projecting beyond the front end of the trackway at its forward end and that it is desired to make a cut upon the bottom, that is, it is desired to insert a kerf whose lower bounding surface will be an extension of the surface along which the track is laid. Starting with the parts in the position shown in Fig. 1, the hand wheel 95 will be operated to engage the clutch 93, and this having been done and the motor being in operation and driving the shaft 15 in a clockwise direction in Fig. 4, the latter will cause the shaft 72 to rotate in a counterclockwise direction, as seen in Fig. 3 and will cause the gear 83 to be rotated in a clockwise direction thereby effecting rotation of the worm 87 similarly. By reason of the nature of this worm, the worm wheel 91 will rotate in a counterclockwise direction viewed from the right in Fig. 3 and the worm 97 will accordingly cause the worm wheel 98 to turn in a counterclockwise direction in Fig. 3. This will result in a swinging of the member 38 from the position shown in Fig. 1 to the position shown in Figs. 3 and 4 and when it has reached the desired position the clutch 93 will be released and the member 38 will be held in locked position by the cooperation of the worm 97 and worm wheel 98. It will be understood that during this operation the clutch mechanism 25 has been left in such position that the cutter chain is not circulated. Simultaneously with the swinging of the parts about the axis of the shaft 72, there has been occurring, due to the manipulation of the controls for the bar swinging means, a simultaneous swinging of the bar in a clockwise direction in Fig. 3 so that the parts may assume a position such as is shown in Fig. 3 without difficulty, herein the fast bar swing being in the opposite direction to the fast swing for the bar mounting and both being used to position the parts as rapidly as possible. It will be understood, of course, that these parts can be arranged in opposite relation and that, moreover, friction means of a different type from the one shown can be employed so as to permit any effect of the way of swing about the various axes to be accomplished, for example, ordinary manually loaded frictions might be substituted for those illustrated. It will be observed that the pitch or lead of the worms which constitutes portions of the bar swinging mechanism will preferably be much steeper than that of the worms 86, 87, this being due to the fact that there is a substantial speed reduction between these worms and the shaft 72. The proportions of the parts and the pitch of the worm 34 will also preferably be varied so that the rate of angular swing will be the same for the bar and for the mechanism which swings the bar bodily, and so also the slow feed mechanisms, or perhaps preferably the bar swing will be a little slower, it being obvious that since the shaft 24 rotates in an opposite direction to the shaft 72, the bar will swing in the opposite direction about its pivot to that in which it is swung bodily. The motor will next be temporarily reversed, all of the swing controlling clutches having been released, and the clutch 50 will be thrown up to hold the friction clutch tight and accordingly the bar will then be lowered down upon the bottom as the nut 42 will rotate in such a direction as to

cause the screw 56 to move downwardly. When the bar is resting on the bottom the clutch 50 will be moved in the opposite direction and will connect the teeth or splines 46', 51 so that the shaft 24 may rotate without relative movement between the frames 40, 31. The machine will then be ready for the starting of the sumping cut and the sprocket 10 may then be rotated, the motor having been 10 reversed again, by the mechanism provided for this purpose in the proper direction to feed the machine along the track and the bar into the coal, the bar then being driven by the engagement of the cutter chain driving sprocket 23 and the shaft 24 by the clutch 25. When the machine is moved forward so that the bar has been sumped into the coal to nearly its full length, the machine will be stopped and held stationary, this 15 being accomplished by the feeding mechanism of the type described. The clutch 92 and the corresponding clutch upon the frame 31 will then be actuated, clutch slippage being permitted so that the kerf started 20 may be carried forward further in the same line. When the bar pivot and the pivot 72 lie in the same vertical plane with the longitudinal axis of the cutter bar, the clutch controlling the slow swinging worm of the 25 bar swinging mechanism will be thrown out and the swing will then proceed entirely about the axis of the shaft 72 until the cut has proceeded to a like position on the opposite side. The slow feed swing for the bar will 30 again be thrown in at this point and while slipping to some extent will be operated in such manner that the point of the bar will remain substantially stationary while the bar pivot will move further until the position 35 the reverse of that shown in Fig. 3 will be reached. The line may then backed out. With the parts the reverse of that shown in Fig. 3, there will be no withdrawal cut necessary. The proportions of the machine 40 shown are, of course, not obligatory, and the frame 38 may be lengthened so as to bring the shaft 24 and the cutter bar further outside the trackway and the bar may be presented to the coal at various angles. After 45 the desired cut has been completed the manipulation of the necessary controls will bring the parts back to the position shown in Fig. 1 and the machine may be run off to another face. Various other possible modes 50 of cutting will be apparent to any one skilled in this art when the structure of this machine is appreciated, but it is not believed necessary to enlarge upon this in order that my invention may be adequately understood. 55 While I have in this application specifically 56 des ribed one form which my invention may assume in practice, it will be understood that this form of the same is shown for purposes of illustration and that the invention may 60 be modified and embodied in various other

forms without departing from its spirit or the scope of the appended claims.

What I claim as new and desire to secure by Letters Patent is:

1. In a wheeled mining apparatus, in combination, guiding means, a support movable longitudinally thereof, self-contained power operated support-wheel driving mechanism for effecting opposite rectilinear movements of said support at a cutting speed, cutting mechanism including a cutter bar, a support to which said bar is pivotally connected for swinging movement, said second mentioned support being pivotally connected to said first mentioned support for movement about an axis parallel to the axis of swing of said cutter bar, a motor driven power shaft journaled on said first mentioned support rotatable on an axis which remains at all times in a vertical plane parallel to the direction of said guiding means, and driving connections between said shaft and said cutting mechanism 70

2. In a mining apparatus, in combination, guiding means, a wheeled support movable longitudinally thereof, self-contained power operated support-wheel driving mechanism for effecting opposite rectilinear movements of said support at a cutting speed, cutting mechanism including a cutter bar, a support to which said bar is pivotally connected for swinging movement, said second mentioned support being pivotally connected to said first mentioned support for movement about an axis parallel to the axis of swing of said cutter bar, a motor driven power shaft journaled on an axis which remains at all times in a vertical plane parallel to the direction of said guiding means, and driving connections between said shaft and said cutting mechanism 80

3. In a mining machine, in combination, guiding means, a wheeled support movable longitudinally thereof, self-contained power operated support-wheel driving mechanism for effecting opposite rectilinear movements of said support at a cutting speed, a horizontal motor driven power shaft thereon fixed as to movement about a vertical axis, cutting mechanism actuated by said shaft including a cutter bar, a support to which said bar is pivotally secured, said last mentioned support being pivoted to said first mentioned support for swinging movements about an axis parallel to the axis of bar swing and in front of said power shaft, and power connections between said shaft and bar whereby the latter may be 100 actuated.

4. In a mining mechanism, in combination, guiding means, a wheeled support movable longitudinally thereof, self-contained power operated support-wheel driving mechanism for effecting opposite rectilinear movements of said support at a cutting speed, a horizontal motor driven power shaft mounted on said support and fixed relative thereto as to movement out of a vertical longitudinally extend- 110

ing plane parallel to the major dimension of said support, a cutter bar, a support to which said cutter bar is pivotally connected, said second mentioned support being pivotally connected to said first mentioned support for pivoting on an axis parallel to the axis of swing of said cutter bar, driving connections between said shaft and said cutter bar, and power connections with said shaft for swinging said bar relative to said second mentioned support.

5. In a mining machine, in combination, guiding means, a wheeled support movable longitudinally thereof, self-contained power operated support-wheel driving mechanism for effecting opposite rectilinear movements of said support at a cutting speed, a horizontal motor driven power shaft thereon fixed as to movement about a vertical axis, a cutter bar, a support to which said bar is pivotally secured, said second mentioned support being pivoted to said first mentioned support for swinging movement about an axis parallel to the axis of bar swing and in front of said power shaft, power connections between said shaft and bar whereby the latter may be actuated, and power connections with said shaft for effecting swinging of said bar relative to said second mentioned support.

30 6. In a mining mechanism, in combination, guiding means, a wheeled support movable longitudinally thereof, self-contained power operated support-wheel driving mechanism for effecting opposite rectilinear movements of said support at a cutting speed, a horizontal motor driven power shaft mounted on said support and fixed relative thereto as to movements out of a vertical longitudinally extending plane parallel to the major dimension of said support, a cutter bar, a support to which said cutter bar is pivotally connected, said second mentioned support being pivotally connected to said first mentioned support for pivotal movement on an axis parallel to the axis of swing of said cutter bar, driving connections between said shaft and said cutter bar, and power operated connections between said shaft and said second mentioned support for effecting bodily swing of said bar and its pivot.

7. In a mining machine, in combination, guiding means, a wheeled support movable longitudinally thereof, self-contained power operated support-wheel driving mechanism for effecting opposite rectilinear movements of said support at a cutting speed, a horizontal motor driven power shaft thereon fixed as to movement about a vertical axis, a cutter bar, a support to which said bar is pivotally secured for swinging movement, said second mentioned support being pivoted to said first mentioned support for swinging movement about an axis parallel to the axis of bar swing, power connections between said shaft and bar whereby the latter may be

actuated, and power connections between said shaft and said second mentioned support for effecting bodily swing of said cutter bar and its pivot.

8. In a mining machine, in combination, guiding means, a support movable longitudinally thereof, a horizontal motor driven power shaft mounted on said support and fixed relative thereto as to movement out of a vertical longitudinally extending plane parallel to the major dimension of said support, a cutter bar, a support to which said bar is pivotally connected, said second mentioned support being pivotally connected to said first mentioned support for pivotal movement upon an axis parallel to the axis of swing of said cutter bar, driving connections between said shaft and said cutter bar, power connections with said shaft for effecting swing of said bar relative to said second mentioned support, and power connections with said shaft for swinging said second mentioned support and said cutter bar relative to said first mentioned support.

9. In a mining machine, in combination, guiding means, a support movable longitudinally thereof, a horizontal motor driven power shaft thereon fixed as to movement about a vertical axis, a cutter bar, a support to which said bar is pivotally secured, said second mentioned support being pivotally connected to said first mentioned support for swinging movement about an axis parallel to the axis of bar swing, power connections between said shaft and bar whereby the latter may be actuated, power connections with said shaft for effecting swing of said bar, and power connections for effecting swing of said second mentioned support and with it said bar relative to said first mentioned support.

10. In a mining mechanism, in combination, guiding means, a support movable longitudinally thereof, a horizontal power shaft rotatable on said support but fixed as to movement about a vertical axis passing through said support, a support rotatable on an axis constantly parallel to a line parallel to the axis of said power shaft, a support rotatable on said second mentioned support upon a pivot perpendicular to the pivot of said second mentioned support, and a cutter bar pivotally connected to said third mentioned support for pivotal movement about an axis parallel to the pivot of said third mentioned support.

11. In a mining mechanism, in combination, guiding means, a wheeled support movable longitudinally thereof, self-contained power operated support-wheel driving mechanism for effecting opposite rectilinear movements of said support at a cutting speed, a horizontal longitudinally extending power shaft on said support, a cutter bar actuated by said shaft, and means for supporting said cutter bar permitting its disposition on the

bottom outside of said guiding means including a support pivoted on a vertical axis in front of said power shaft.

12. In a mining machine, a truck adapted to run upon a track and having supporting wheels, a member rotatable upon a vertical axis disposed in front of said truck wheels, cutting mechanism supported by said member and including a pivoted cutter bar swingable about an axis parallel to said vertical axis and provided with cutting elements moving in an orbit within which the pivot of the bar is disposed, and power operated means whereby said bar may be disposed in a transverse plane beneath the top of the track when it lies wholly outside one side of the track.

13. In a mining machine, a truck adapted to run upon a track and having supporting wheels, a member rotatable upon a vertical axis disposed in front of said truck wheels, cutting mechanism supported by said member and including a pivoted cutter bar swingable about an axis parallel to said vertical axis and provided with cutting elements moving in an orbit within which the pivot of the bar is disposed, power operated means whereby the bar may be disposed in a transverse plane beneath the top of the track when it is wholly outside one side of the track, and power operated means whereby the bar may be swung about its pivot.

14. In a mining machine, a truck adapted to run upon a track and having supporting wheels, a member rotatable upon a vertical axis disposed in front of said truck wheels, cutting mechanism supported by said member and including a pivoted cutter bar swingable about an axis parallel to said vertical axis and provided with cutting elements moving in an orbit within which the pivot of the bar is disposed, power operated means whereby the bar may be disposed in a transverse plane beneath the top of the track when it is wholly outside one side of the track, power operated means whereby the bar may be swung about its pivot, and power operated means for moving said bar when so disposed to bring its pivot to the opposite side of the track.

15. In a mining machine, a truck adapted to run upon a track and having supporting wheels, a member rotatable upon a vertical axis disposed in front of said truck wheels, cutting mechanism supported by said member and including a pivoted cutter bar swingable about an axis parallel to said vertical axis and provided with cutting elements moving in an orbit within which the pivot of the bar is disposed, power operated means whereby the bar may be disposed in a transverse plane beneath the top of the track when it is wholly outside one side of the track, power operated means whereby the bar may be swung about its pivot, power operated means for moving said bar when so disposed to bring its pivot to the opposite side of the

track, and power operated means for moving said truck in opposite directions along said track.

16. In a mining machine, a truck adapted to run upon a track, a power operated horizontal longitudinally extending shaft on said truck, a cutter bar, and means for supporting the same during horizontal cutting including parts rotatable about a horizontal axis parallel to a line parallel to the axis of said power shaft and including a plurality of pivots disposable in the vertical plane to which said track is parallel and intermediate the opposite sides of said track, one of said pivots being in such position of the parts further forward than 80 to said horizontal axis.

17. In a mining machine, a truck adapted to run upon a track, a power operated horizontal longitudinally extending shaft on said truck, a cutter bar, and means for supporting the same including parts rotatable about a horizontal axis parallel to a line parallel to the axis of said power shaft and including a plurality of vertical pivots disposable in the vertical plane to which said track is parallel and intermediate the opposite sides of said track, one of said pivots being in such position of the parts further forward than and below the other and both of said pivots being perpendicular to said horizontal axis.

18. In a mining machine, a truck adapted to run upon a track, a power operated horizontal longitudinally extending shaft on said truck, a cutter bar, and means for supporting the same including parts rotatable about a horizontal axis parallel to a line parallel to the axis of said power shaft and including a plurality of vertical pivots disposable in the vertical plane to which said track is parallel and intermediate the opposite sides of said track, one of said pivots being in such position of the parts further forward than the other and both of said pivots being perpendicular to said horizontal axis, and means for varying the relative height of said pivots while in said plane.

19. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second support on said frame permitting rotation on a horizontal axis, and driving connections between said shaft and said cutter bar.

20. In a mining mechanism, in combination, guiding means, a frame movable longi-

tudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis parallel to a line parallel to said power shaft, and driving connections between said power shaft and said cutter bar.

21. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis in alignment with said power shaft, and driving connections between said power shaft and said cutter bar.

22. In a mining mechanism, in combination, guiding means, a support movable longitudinally thereof, a motor driven power shaft mounted on said support and fixed relative thereto as to movement out of a vertical longitudinally extending plane parallel to the major dimension of said support, a cutter bar, a second support to which said cutter bar is pivotally connected for swinging movement, a third support to which said second mentioned support is pivotally connected on an axis parallel to the axis of swing of said cutter bar, a pivotal mounting for said third support on said frame permitting rotation on a horizontal axis, driving connections between said shaft and said cutter bar, and power operated mechanism for effecting pivotal movement of one of said supports about its axis of rotation.

23. In a mining mechanism, in combination, guiding means, a support movable longitudinally thereof, a motor driven power shaft mounted on said support and fixed relative thereto as to movement out of a vertical longitudinally extending plane parallel to the major dimension of said support, a cutter bar, a second support to which said cutter bar is pivotally connected for swinging movement, a third support to which said second mentioned support is pivotally connected on an axis parallel to the axis of swing of said cutter bar, a pivotal mounting for said second mentioned support on said frame permitting rotation thereof on an axis parallel to a line parallel to said power shaft, driving connections between said power shaft and said cutter bar, and power operated mechanism for effecting

support permitting rotation thereof on an axis parallel to a line parallel to said power shaft, driving connections between said power shaft and said cutter bar, and power operated mechanism for effecting pivotal movement of one of said supports about its axis of rotation.

24. In a mining mechanism, in combination, guiding means, a support movable longitudinally thereof, a motor driven power shaft mounted on said support and fixed relative thereto as to movement out of a vertical longitudinally extending plane parallel to the major dimension of said support, a cutter bar, a second support to which said cutter bar is pivotally connected for swinging movement, a third support to which said second mentioned support is pivotally connected on an axis parallel to the axis of swing of said cutter bar, a pivotal mounting for said third support on said first mentioned support permitting rotation thereof on an axis in alignment with said power shaft, driving connections between said power shaft and said cutter bar, and power operated mechanism for effecting pivotal movement of one of said supports about its axis of rotation.

25. In a mining mechanism, in combination, guiding means, a support movable longitudinally thereof, a motor driven power shaft mounted on said support and fixed relative thereto as to movement out of a vertical longitudinally extending plane parallel to the major dimension of said support, a cutter bar, a second support to which said cutter bar is pivotally connected for swinging movement, a third support to which said second mentioned support is pivotally connected on an axis parallel to the axis of swing of said cutter bar, a pivotal mounting for said third support permitting rotation on a horizontal axis, driving connections between said shaft and said cutter bar, and power operated mechanism for effecting pivotal movement of either of said second or said third mentioned supports about their respective axes of rotation.

26. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis parallel to a line parallel to said power shaft, driving connections between said power shaft and said cutter bar, and power operated mechanism for effecting

pivotal movement of either of said supports about their respective axes of pivoting.

27. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis in alinement with said power shaft, driving connections between said power shaft and said cutter bar, and power operated mechanism for effecting pivotal movement of either of said supports about its respective axis of pivoting.

28. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second support on said frame permitting rotation on a horizontal axis, driving connections between said shaft and said cutter bar, and power operated mechanism for effecting pivotal movement of either of said supports or of said bar about its respective axis of pivoting.

29. In a mining mechanism, in combination, guiding means, a frame movable longitudinally thereof, a motor driven power shaft mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis parallel to a line parallel to said power shaft, driving connections between said power shaft and said cutter bar, and power operated mechanism for effecting pivotal movement of each of said supports and of said bar about its respective axis of pivoting.

30. In a mining mechanism, in combination, guiding means, a frame movable longitudinally thereof, a motor driven power shaft

mounted on said frame and fixed relative thereto as to movement out of a vertical longitudinally extending plane parallel to the major dimension of said frame, a cutter bar, a support to which said cutter bar is pivotally connected for swinging movement, a second support to which said first mentioned support is pivotally connected on an axis parallel to the axis of swing of said cutter bar, a pivotal mounting for said second mentioned support on said frame permitting rotation thereof on an axis in alinement with said power shaft, driving connections between said power shaft and said cutter bar, and power operated mechanism for effecting pivotal movement of each of said supports and of said bar about its respective axis of pivoting.

31. In a mining machine, in combination, guiding means, a frame movable longitudinally thereof, a motor driven power shaft thereon fixed as to movement about a vertical axis, a cutter bar, a support to which said bar is pivotally secured for swinging movement, a second support to which said first mentioned support is pivoted for swinging movement about an axis parallel to the axis of bar swing and in front of said first mentioned axis, a pivotal mounting for said second mentioned support on said frame permitting pivoting thereof on an axis extending longitudinally of said guiding means, and power connections between said shaft and bar whereby the latter may be actuated.

32. In a mining machine, in combination, guiding means, a frame movable longitudinally thereof, a motor driven power shaft thereon fixed as to movement about a vertical axis, a cutter bar, a support to which said bar is pivotally secured for swinging movement, a second support to which said first mentioned support is pivoted for swinging movement about an axis parallel to the axis of bar swing and in front of said shaft, a pivotal mounting for said second mentioned support on said frame permitting pivoting thereof on an axis extending longitudinally of said guiding means, power connections between said shaft and bar whereby the latter may be actuated, and power operated mechanism for effecting pivotal movement of one of said supports about its axis.

33. In a mining machine, in combination, guiding means, a frame movable longitudinally thereof, a motor driven power shaft thereon fixed as to movement about a vertical axis, a cutter bar, a support to which said bar is pivotally secured for swinging movement, a second support to which said first mentioned support is pivoted for swinging movement about an axis parallel to the axis of bar swinging and in front of said shaft, a pivotal mounting for said second mentioned support on said frame permitting pivoting thereof on an axis extending longi-

tudinally of said guiding means, power connections between said shaft and bar whereby the latter may be actuated, and power operated mechanism for effecting pivotal movement of either of said supports about its respective axis.

34. In a mining machine, in combination, guiding means, a frame movable longitudinally thereof, a motor driven power shaft thereon fixed as to movement about a vertical axis, a cutter bar, a support to which said bar is pivotally secured for swinging movement, a second support to which said first mentioned support is pivoted for swinging movement about an axis parallel to the axis of bar swing and in front of said shaft, a pivotal mounting for said second mentioned support on said frame permitting pivoting thereof on an axis extending longitudinally of said guiding means, power connections between said shaft and bar whereby the latter may be actuated, and power operated mechanism for effecting pivotal movement of either of said supports or of said bar about its respective axis of pivoting.

35. In a mining machine, a machine frame including a motor fixed as to rotation about a vertical axis, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means permitting disposition of said pivots in different planes intersecting in a line parallel to the axis of rotation of the motor.

36. In a mining machine, a machine frame, including a motor fixed as to rotation about a vertical axis, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means permitting disposition of said pivots in different planes intersecting in a line parallel to the axis of rotation of the motor and for changing their relative disposition in such planes.

37. In a mining machine, a machine frame including a motor fixed as to rotation about a vertical axis, cutting mechanism driven by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and disposed wholly in front of the motor, and means for changing the distance apart of said pivots while they remain parallel.

38. In a mining apparatus, a machine frame including a motor having a horizontal axis of rotation extending constantly longitudinally of said machine frame, a cutter bar carrying cutting elements orbitally moved by said motor, and supporting and adjusting mechanism for said cutter bar providing a pivot perpendicular to the plane of cut of the bar about which the bar may swing, a parallel pivot about which said first mentioned pivot and said bar may swing, and means coaxial with one of said pivots for effecting rectilinear adjustment of said bar in a direction parallel to said pivots.

39. In a mining apparatus, a machine frame including a motor having a horizontal axis of rotation extending constantly longitudinally of said machine frame, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means coaxial with said bar pivot for effecting adjustment of said bar rectilinearly along said pivot by power from said motor.

40. In a mining apparatus, a machine frame including a motor having a horizontal axis of rotation extending constantly longitudinally of said machine frame, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means for changing the plane of each of said pivots.

41. In a mining apparatus, a machine frame including a motor having a horizontal axis of rotation extending constantly longitudinally of said machine frame, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means for disposing said pivots in a horizontal or in a vertical plane.

42. In a mining apparatus, a machine frame including a motor having a horizontal axis of rotation extending constantly longitudinally of said machine frame, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means for disposing said pivots in a vertical plane and

- above or below the axis of rotation of said motor.
43. In a mining apparatus, a machine frame including a motor having a horizontal axis of rotation extending constantly longitudinally of said machine frame, cutting mechanism actuated by said motor including a cutter bar, and supporting and adjusting mechanism for said cutter bar providing a pivot perpendicular to the plane of cut of the bar about which the bar may swing, a parallel pivot about which said first mentioned pivot and said bar may swing, and means for disposing said pivots in a horizontal plane at either side of the axis of rotation of said motor.
44. In a mining machine, a truck adapted to run upon a track, cutting mechanism thereon having a pivoted cutter bar provided with cutting elements moving in an orbit within which the pivot of said bar is disposed, and means whereby said bar may be disposed in a transverse plane beneath the top of said track with its pivot at one side of said track including means for changing the plane of swing of said bar including concentric elements coaxial with the pivot of the latter and cooperating on relative movement to effect a change in plane of bar swing.
45. In a mining apparatus, a portable body, a motor carried thereby, a support pivotally mounted on said body for rotation through at least ninety degrees about a horizontal axis, a second horizontally swingable support pivotally mounted on said first support for rotation about an axis perpendicular to said axis, and cutting mechanism driven by said motor including a cutter bar pivotally mounted on said second support for horizontal swinging movement relative thereto.
46. In a mining apparatus, a portable body, a motor carried thereby, a support pivotally mounted on said body for rotation through at least ninety degrees about a horizontal axis, a second support pivotally mounted on said first support for rotation about an axis perpendicular to said axis, cutting mechanism driven by said motor including a cutter bar pivotally mounted on said second support for swinging movement relative thereto, and means driven by said motor for adjusting the plane of said cutter bar relative to said second support.
47. In a mining apparatus, a portable body, a motor carried thereby, a support pivotally connected to said body for rotation through at least ninety degrees about a horizontal axis, a second support pivotally connected to said first support for rotation about an axis perpendicular to said axis, cutting mechanism driven by said motor including a cutter bar pivotally connected to said second support for swinging movement relative thereto, and mechanism driven by said motor for rotating said first support relative to said body, for rotating said second support relative to said first support, for adjusting said third support relative to said second support, and for swinging said cutter bar relative to said third support.
48. In a mining apparatus, a portable body, a motor carried thereby, a support pivotally mounted on said body for rotation through at least ninety degrees about a horizontal axis, a second support pivotally mounted on said first support for rotation about an axis perpendicular to said axis, and cutting mechanism driven by said motor including a cutter bar pivotally mounted on said second support for swinging movement relative thereto about an axis parallel to the axis of said second support.
49. In a mining apparatus, a portable body, a motor carried thereby, a support pivotally mounted on said body for rotation through at least ninety degrees about a horizontal axis, a second support pivotally mounted on said first support for rotation about an axis perpendicular to said axis, cutting mechanism driven by said motor including a cutter bar pivotally mounted on said second support for swinging movement relative thereto about an axis parallel to the axis of said second support, and mechanism driven by said motor for adjusting the plane of said cutter bar relative to said second support.
50. In a mining apparatus, a portable body, a motor carried thereby, a support pivotally mounted on said body upon a horizontal axis for rotary movement through at least ninety degrees, a second support pivotally mounted on said first support for rotation about an axis perpendicular to said axis, a third support slidably mounted on said second support, and cutting mechanism driven by said motor including a cutter bar pivotally mounted on said third support for swinging movement relative thereto.
51. In a mining apparatus, a portable body, a motor carried thereby, a support pivotally mounted on said body upon a horizontal axis for rotary movement through at least ninety degrees, a second support pivotally mounted on said first support for rotation about an axis perpendicular to said axis, a third support slidably mounted on said second support, cutting mechanism driven by said motor including a cutter bar pivotally mounted on said third support for swinging movement relative thereto, and mechanism driven by said motor for rotating said first support relative to said body, for rotating said second support relative to said first support, for adjusting said third support relative to said second support, and for swinging said cutter bar relative to said third support.
52. In a mining apparatus, a portable body, a motor carried thereby, a support pivotally mounted on said body for rotation through at least ninety degrees about a horizontal axis, a second support pivotally mounted on

said first support for rotation about an axis perpendicular to said axis, a third support guided on said second support for movement in a plane parallel to the axis of said second support, and cutting mechanism driven by said motor including a cutter bar pivotally mounted on said third support for swinging movement relative thereto.

53. In a mining apparatus, a portable body, a motor carried thereby, a support pivotally mounted on said body for rotation through at least ninety degrees about a horizontal axis, a second support pivotally mounted on said first support for rotation about an axis perpendicular to said axis, a third support guided on said second support for movement in a plane parallel to the axis of said second support, cutting mechanism driven by said motor including a cutter bar pivotally mounted on said third support for swinging movement relative thereto, and mechanism driven by said motor for rotating said first support relative to said body, for rotating said second support relative to said first support, for adjusting said third support relative to said second support, and for swinging said cutter bar relative to said third support.

54. In a mining apparatus, a portable body adapted to run along a trackway, a motor carried by said body, mechanism driven by said motor for propelling said body along said trackway in opposite directions at different speeds, a support pivotally mounted on said body for rotation through at least ninety degrees about a horizontal axis, a second support pivotally mounted on said first support for rotation about an axis perpendicular to said axis, a third support adjustably mounted on said second support, and cutting mechanism driven by said motor including a cutter bar pivotally mounted on said third support for swinging movement relative thereto.

55. In a mining apparatus, a portable body adapted to run along a trackway, a motor carried by said body, mechanism driven by said motor for propelling said body along said trackway in opposite directions at different speeds, a support pivotally mounted on said body for rotation through at least ninety degrees about a horizontal axis, a second support pivotally mounted on said first support for rotation about an axis perpendicular to said axis, a third support adjustably mounted on said second support for movement in a plane parallel to the axis of said second support, and cutting mechanism driven by said motor including a cutter bar pivotally mounted on said third support for movement relative thereto.

56. In a mining apparatus, a portable body, a motor carried thereby, a support rotatably mounted on said body for rotation through at least ninety degrees on a horizontal axis, a second support pivotally mounted on said first support, the axis of said second support

being perpendicular to the axis of said first support, a third support adjustably mounted on said second support and adjustable relative thereto by power from said motor, and cutting mechanism driven by said motor including a cutter bar pivotally mounted on said third support for swinging movement relative thereto.

57. In a mining apparatus, a portable body, a motor carried thereby, a support rotatably mounted thereon for rotation through at least ninety degrees about a horizontal axis, a second support pivotally mounted on said first support, the axes of said supports being perpendicular to each other, a third support slidably guided on said second support for movement toward and from the axis of said first support, and cutting mechanism driven by said motor including a cutter bar pivotally mounted on said third support for swinging movement relative thereto.

58. In a mining apparatus, a portable body, a motor carried thereby, a support rotatably mounted thereon for rotation through at least ninety degrees about a horizontal axis, a second support pivotally mounted on said first support, the axes of said supports being perpendicular to each other, a third support slidably guided on said second support for movement toward and from the axis of said first support, cutting mechanism driven by said motor including a cutter bar pivotally mounted on said third support for swinging movement relative thereto, and mechanism driven by said motor for rotating said first and second supports about their axes, for adjusting said third support relative to said second support, and for swinging said cutter bar.

59. In a mining apparatus, a portable body, a motor carried thereby, a support pivotally mounted on said body for rotation through at least ninety degrees about a horizontal axis, a second support pivotally mounted on said first support for rotation about an axis perpendicular to said axis, a third support adjustably mounted on said second support, cutting mechanism driven by said motor including a cutter bar pivotally mounted on said third support for swinging movement relative thereto, and mechanism driven by said motor for swinging said second support relative to said first support and said cutter bar relative to said third support at different speeds in opposite directions.

60. In a mining apparatus, a portable body, a motor carried thereby, a support pivotally mounted on said body for rotation through at least ninety degrees about a horizontal axis, a second support pivotally mounted on said first support for rotation about a vertical axis, said second support being swingable to a position at a right angle to the major axis of the apparatus, a third support slidably guided on said second support for move-

ment toward and from the axis of said first support, and cutting mechanism driven by said motor including a cutter bar pivotally mounted on said third support for swinging 5 movement relative thereto.

61. In a mining apparatus, a portable body, a motor carried thereby, a support pivotally mounted on said body for rotation through at least ninety degrees about a horizontal 10 axis, a second support pivotally mounted on said first support for rotation about a vertical axis, said second support being swingable to a position at a right angle to the major axis of the apparatus, a third support 15 slidably guided on said second support for movement toward and from the axis of said first support, cutting mechanism driven by said motor including a cutter bar pivotally mounted on said third support for swinging movement relative thereto, and mechanism driven 20 by said motor for adjusting said third support relative to said second support and for swinging said cutter bar about its pivot.

62. In a mining apparatus, a portable body 25 adapted to run along a trackway, a motor carried thereby and permanently fixed against angular movement relative thereto, a support pivotally mounted on said body for rotation about a vertical axis, cutting mechanism 30 driven by said motor adjustably mounted on said support for bodily translatory movement relative thereto and including a pivoted cutter bar, mechanism driven by said motor for swinging said support about its axis, and 35 mechanism driven by said motor for adjust-

ing said cutting mechanism to bring said cutter bar below the level of the trackway.

63. In a mining apparatus, a portable body adapted to run along a trackway, a motor carried by said body in permanently fixed angular relation thereto, a support pivotally mounted on said body for rotation about a vertical axis, cutting mechanism driven by said motor including a cutter bar pivotally mounted on said support for pivotal movement relative thereto about an axis parallel to the axis of said support, and mechanism driven by said motor for swinging said support to bring said cutter bar axis wholly outside of the trackway to enable the cutter bar 40 to operate on the mine bottom and for swinging said bar independently of said support. 45

64. In a mining apparatus, a wheeled body adapted to run along a trackway and always having its major dimension extending longitudinally of the trackway, a motor carried by said body in permanently fixed rigid relation thereto, cutting mechanism actuated by said motor including a cutter bar, and supporting and adjusting mechanism for said cutter bar 50 providing a pivot perpendicular to the plane of cut of the bar about which the bar may swing, a parallel pivot about which said first mentioned pivot and said bar may swing, and means coaxial with one of said pivots for effecting adjustment of said bar by power from said motor in a direction parallel to said pivot. 55

In testimony wherof I affix my signature.
CHARLES F. OSGOOD.
